UNITED STATES PATENT OFFICE.

MARY HORWITZ, OF GLOVERSVILLE, NEW YORK, ASSIGNOR TO HARRIS LAZARUS, OF GLOVERSVILLE, NEW YORK.

FUR LINING FOR GLOVES.

Application filed March 29, 1924. Serial No. 702,945.

To all whom it may concern:

Be it known that I, MARY HORWITZ, a citizen of the United States, and a resident of Gloversville, in the county of Fulton and State of New York, have invented certain new and useful Improvements in Fur Linings for Gloves, and do hereby declare that the following is a full, clear, and exact description thereof, which will enable others skilled in the art to which it appertains to make and use the same, reference being had to the accompanying drawings, and to the reference numerals marked thereon, which form part of this specification.

My present invention relates to the fur lining of gloves and particularly to the fur linings as commonly formed separate from the shell or outside of the glove.

The purpose of my invention is to provide a new and improved form of fur lining for gloves, and particularly to provide a form of fur lining of such arrangement that the weaker part of the skin and the thinner and poorer colored fur will be located respectively where the wear and strain is least and where the poorer fur is less noticeable and in fact partly permanently concealed, and furthermore, to have the lining of such arrangement that the strongest part of the skin and the better furred part along with the perfect blending of color as in the natural state will extend across the entire glove where the strain is greater and where the color and the wearing quality of the fur is exposed and is constantly observed by the wearer.

A further purpose of my invention is to provide a fur lining for gloves where the stomach edges of the relatively small fur bearing skins used for the linings will be located lengthwise of the center of the palm of the hand and along the edges of the button or other fastening opening.

A further purpose of my invention is to provide a glove lining of the character above described in combination with a glove shell of ordinary construction.

Further purposes and advantages of my invention will appear in the specification and claims herein.

Fig. 1 shows a full glove fur lining blank as formed or cut in accordance with my in-

vention with the outline of the skin from which the blank is cut shown in dotted lines.

Fig. 2 is a view of the inner or palm side 55 of the lining formed from said blank with the usual addition of the thumb.

Fig. 3 is a view of the palm side of a complete glove, formed with a lining embodying my invention.

Fig. 4 is a sectional view on line 4—4 of Fig. 2; but with the front and back separated as when in use.

Fig. 5 is a similar sectional view on line 5—5 of Fig. 3.

Fig. 6 is a sectional view similar to Fig. 5, showing a fur lining embodying my invention when a wider binding strip is used at the edges of the main or bottom opening of the glove. Fig. 7 is a similar sectional 70 view through a fur lined glove as heretofore made.

Fur lined gloves are made by combining an outer shell of leather or other durable material with a separately formed fur lining. These fur linings in turn are made up from a blank formed from fur bearing skins.

For such fur linings rabbit skins are the ones commonly used on account of their 80 relative low cost and the pleasing color of the rabbit fur and because the hair and hide are best suited for gloves. Rabbit skins and the skins of other animals that may be practicable to use for such linings are only 85 a little larger than the lining blank to be cut therefrom so that the longitudinal edges of the blank practically coincide with or come very close to the longitudinal edges of the fur bearing skin. The side edges of the 90 skin are formed from the original slitting of the skin up through the lower central line of the animal, that is through the center of the stomach and chest.

The skin adjacent the side edges is 95 appreciably thinner and weaker than the skin at the back of the animal and the fur adjacent the side edges is decidedly thinner and poorer than upon the rest of the skin. It happens also that the ordinary brown or gray rabbits the skins from which are commonly used for glove linings, have a streak of very much lighter fur and on most skins this lighter streak at its center is white. It 100

follows, therefore, that there is at each side edge of the skin and accordingly at each side edge of the full glove blank formed therefrom a strip of decidedly poorer and weaker skin and of decidedly lighter colored or white fur and poorer fur.

Heretofore the universal arrangement of the fur bearing skin in the lining has been to have the edges of the skin come together 10 in a seam along the outside of the little finger and up that edge of the hand and wrist portion of the glove. This is the common method of forming the shell of a glove formed of a piece of leather as is illustrated 15 in Fig. 3. In the forming of the lining, however, this previous arrangement had the disadvantage that it brought all of the white or lighter colored and poorer fur and the poorer skin together in a mass along the little 20 finger edge of the glove.

Fig. 7 is a sectional and somewhat diagrammatic view of the previous construction of glove lining. This discloses the objectional massing and showing of the white fur 25 at the little finger edge of the glove.

In the formation of fur linings according to my invention, the pattern is so arranged and the blank 8 formed thereby from the fur bearing skin 9 so that the longitudinal 30 sides 10—10 of the skin 9 are brought together at the center of the palm of the hand and are brought towards each other at the button opening 11 of the glove. This is done by forming the pattern and therewith the 35 blank 8 as shown particularly in Fig. 1, so that one edge 12 of the blank is in line with the inner edge of the front 13 of the third finger while the other edge 14 of the blank is in line with the adjacent or inner edge of the inside or palm side of the middle or 40 second finger 15.

With the side edges 12 and 14 of the blank so made there is of course also formed upon the blank the other parts of the fingers proceeding from the front 15 of the middle finger as follows: The front 16 of the first finger, the back 17 of the first finger, the back 18 of the middle finger, the back 19 of the third finger; the back 20 of the little finger and the front 21 of the little finger. 45 There is also cut the usual U-shaped hole 22 for the addition of the separate thumb piece 23 with a tab 24 left from the blank projecting into the aperture 22, said tab being used 50 to help form the thumb.

The blank as thus formed is then folded with the fur side in along the lines 25—25 and 26—26. The extreme ends of the finger pieces are then sewed together with the usual fourchette pieces on the inner edge of the first finger and the inner edge of the little finger and along both edges of the second and third fingers, then the meeting edges 12 and 14 of the blank are sewed together as by

seam 27 through the middle of the palm producing a fully formed fur lining as shown in Fig. 2, it being understood that meanwhile at some convenient stage the separate thumb piece 23 has been separately formed and then sewed to the main body of the lining.

For some types of gloves and for some glove manufacturers the edges 12 and 14 of the blank are sewed together on the line of the seam 27 not only through the center of the palm of the hand, but upwardly to the 70 wrist end of the glove. This is a minor modification not interfering with the invention and this modification is within the scope of several of the claims hereof.

The glove lining thus formed is then placed 80 within the shell 28 of the glove and fastened thereto in the usual manner. This fastening of the shell 28 and the fur lining always includes a secure fastening of the two parts of the complete glove about the cuff end of the 85 glove and along the two edges of the button or fastening opening 11. This fastening is usually accomplished by a binding strip 29 first fastened to the edge of the shell of the glove along both sides of the button opening 90 11. The binding strip is then turned over on the inside against the fur surface of the lining and secured in place by one or usually two rows of stitching 30 and 31, with the 95 stitches extending through the leather of the shell and through the binding on the inside and through the enclosed skin of the lining.

The separate binding may be extended around the cuff end of the glove, but usually the connection between the parts is effected 100 by turning back inwardly a portion of the cuff of the shell.

It will now be seen that the lightest colored portion of the fur lining extends to the center of the palm and along adjacent 105 the button opening 11. The binding strip 29 covers up a very appreciable part of the white or lightest part of the fur. This is especially so in some forms of glove where a relatively wide binding is used but in any 110 event the binding strip is wide enough to cover up some of the most objectional or lightest of the fur. It will also be noticed that such of the light colored fur as is not covered by the binding is separated into two 115 parts adjacent the binding instead of being all massed without any decrease in amount at the little finger edge of the glove as in the old form of lining. It will be further noted especially by comparing Fig. 5 or 6 with Fig. 7 that the darkest colored or richest colored part of the skin is at the center of the back of the glove right opposite the button opening where the fur lining is most noticeable. Also it will be seen that the center of the lining skin is at the back of the glove where there is the most strain in pulling 120 on the glove or closing the hand and that

125

the weakest part of the fur lining is through the center of the palm of the hand where there is no strain at all or towards the wrist along the sides of the button opening where 5 it is directly reinforced by being sewed to the shell of the glove and further reinforced by the inwardly extending binding strip 29.

What I claim as new and desire to secure by Letters Patent is:

10 1. In a fur lined glove the combination of an outer shell formed from a blank having its longitudinal edges brought together at the outside of the little finger and up the glove in line therewith and a fur lining composed of a fur-bearing skin with its stomach

edges located lengthwise of the glove on a line through the center of the palm.

2. In a fur lined glove the combination of an outer shell formed from a blank having its longitudinal edges brought together at 20 the outside of the little finger and up the glove in line therewith and a fur lining composed of a fur-bearing skin with its stomach edges brought to the edges of the button opening at the wrist and into the palm on a 25 line with the center of the palm and brought together through the center of the palm.

In witness whereof I have affixed my signature, this 19th day of February, 1924.

MARY HORWITZ.
